SHOE SEWING MACHINE

Fred Ashworth, Wenham, and Carl F. Whitaker, Beverly, Mass., assignors to United Shoe Machinery Corporation, Flemington, N. J., a corporation of New Jersey

Original application February 2, 1942, Serial No. 429,206. Divided and this application August 13, 1943, Serial No. 498,484

14 Claims. (Cl. 112—47)

The present invention relates to improvements in work-feeding and guiding means for shoe sewing machines and is herein illustrated as embodied in a high-speed lockstitch sewing machine of the hooked needle type, as disclosed in the present inventors' United States Letters Patent No. 2,271,611, granted February 3, 1942, and constructed and arranged to sew the outsole and welted upper of a Goodyear welt shoe.

In outsole shoe sewing machines of the clamp feed type, inequality of spacings between stitches may be produced by variation in the position at which a shoe being operated upon is presented to the machine by an operator. Forcing a shoe against the forward face of the work support or against the back gage of a stitcher with an irregular pressure or holding the edge of the outsole in presenting the shoe to the machine at a slight angle to the natural line of feed, as is often the practice, in order to maintain the edge of the outsole against the back gage with less physical effort, causes the back gage of the machine to impart an outward component of movement to the outsole, thus rendering it easier for the operator to hold the work in position. When the edge of the outsole is given an outward component of movement by the back gage, due to the practice of holding the edge of the outsole at an angle with relation to the line of feed, the seam also tends to follow a line not exactly parallel to the line of feed, especially when there is an abrupt curvature along the edge of the outsole. As a result, the back gage will exert a feed choking drag on the work which may become excessive if the angle at which the edge of the shoe outsole at the point of operation is presented is relatively large. Also due to the angular relation of the seam line to the line of feed, the needle may be looped improperly and the operations of others of the stitch forming devices may be adversely affected.

The particular objects of the present invention are to provide a construction for a high-speed lockstitch outsole shoe sewing machine in which accurate and equal feeding movements will be imparted to the work during sewing and in which the difficulties referred to will be avoided. In general, the objects are to simplify and improve the actuating mechanisms of an outsole sewing machine in a manner to insure accurate formation of stitches both in length and in uniformity with which they are set in the substance of an outsole where the machine is operated at high or moderate speeds, and to prevent irregularity in sewing operations of previous machines in which

such irregularity has resulted from vibration, lost motion in the parts, or from other associated causes.

With these and other objects in view, a feature 5 of the present invention contemplates the provision, in a high-speed outsole shoe-stitching machine, of a mechanism for actuating the work support and presser foot to exert a continued rearward pull at right angles to the line of feed on the outsole near the point of operations throughout and during feeding movements, thus avoiding the necessity of forcing the shoe against the back gage with an irregular feed choking pressure. Consequently, when the shoe is presented to the machine with the edge of the sole 10 at the point of operation more nearly parallel with the line of feed than has been the practice heretofore, a substantially uniform pressure of the sole edge against the back gage may be maintained without variation ordinarily caused by uncertain manipulations of the operator either in pressing the shoe rearwardly or in turning the shoe into a position with the sole edge out of line 15 with the feed line to cause the feeding movement of the shoe to assist in pressing the sole edge against the back gage. The embodiment of this feature of the invention, as hereinafter described, is in a machine in which there is an arcuate movement of the work support and presser foot 20 and a proper timed relation between the work-clamping mechanism for the presser foot and feed-actuating mechanisms. When properly arranged and timed, the pressure of the presser foot is centralized on the work and the point of centralized pressure moves rearwardly and away 25 from the needle while the work is clamped and is being fed. During back feeding movement, the parts of the work support and presser foot which cause the clamping pressure to be centralized 30 move forwardly toward the needle, the presser foot then being raised from the work. To centralize the clamping pressure, in accordance with this feature of the invention, the surfaces of the work support and presser foot are relatively inclined in the direction of work feed to cause the greatest clamping pressure to be exerted at a 35 location on the seam side of the needle.

When no back gage is employed to guide the edge of an outsole being operated upon, it is customary to shape the work support in a wedge form which will readily fit into the crease between the welt and upper of a shoe. When a forward and rearward movement, in addition to the feeding movement, is imparted to the work support, 50 it has been found desirable in the machine of the

present invention to exert the rearward pull on the sole relatively slowly and to actuate the work support with a relatively quick forward thrust, causing it to be wedged into the crease between the welt and upper in order to maintain a uniform grip on the outsole. Also in the illustrated machine, the work support oscillates about an axis at an acute angle to the work-supporting surface of the work support and is so arranged that the thrust of the work-engaging surfaces of the work support exerts substantially equal pressures against both the welt and upper while sewing along the shank of a shoe.

When the work support and presser foot are actuated in the manner just outlined and a back gage not moving with the work support is provided for guiding the edge of an outsole past the point of operation of the stitch-forming devices, there is a tendency for the movements of the work support to cause the lower corner of the welt in a shoe to become wedged between the work support and the gage. In order to prevent the welt from becoming wedged between the work support and gage in the present form of the machine, the gage is constructed with angularly disposed surfaces, one of which guides the welt along that surface engaged by the work support. This feature consists of a gage having a lip upon which the surface of the welt rests and the work support is provided with a shoulder formed at that side of the point of operation of the stitch-forming devices first engaged by the work during back feed of the work support, thus enabling the work-engaging surface of the lip to be located as close as possible to the work-supporting surface of the work support.

Other features of the invention consist in the novel and improved devices, combinations and arrangements of parts hereinafter described and claimed, the advantages of which will be readily understood by one skilled in the art from the following description taken in connection with the accompanying drawings illustrating one embodiment of the invention.

In the drawings;

Fig. 1 is a view in front elevation of a part of an outsole shoe-sewing machine embodying the features of the present invention;

Fig. 2 is a view in side elevation of a portion of the work support and presser foot of the machine illustrated in Fig. 1, together with the novel back gage;

Fig. 3 is a plan view of the work support and back gage;

Fig. 4 is a detail view, partly in section, of the work support carrier, its mounting shaft and feed-actuating mechanism;

Fig. 5 is a diagrammatic plan view on an enlarged scale illustrating the manner of obtaining a rearward pull on the work during work feed;

Fig. 6 is a detail view in elevation and partly in section, of the work support, presser foot and carrier; and

Fig. 7 is a side view on an enlarged scale of the upper part of the work support and a shoe being guided thereby, shown in section.

The machine illustrated in the drawings is of the type disclosed in prior United States Letters Patent of Ashworth No. 1,169,909, granted February 1, 1916; No. 1,824,063, granted September 22, 1931; and No. 2,015,654, granted October 1, 1935, as well as in Patent No. 2,271,611, above referred to, and is of the same construction and mode of operation as that illustrated and described in

inventors' application Serial No. 429,206, filed February 2, 1942, (Patent No. 2,354,729, granted August 1, 1944), of which the present application is a division. The machine is equipped with a curved hook needle 2, a curved awl 4, a thread case 6 mounted within a shuttle or loop taker, needle-threading mechanism including a looper 8 and a thread finger 10, a work support 12, a presser foot 14, back gage 16 and other stitch-forming devices similar to those of the above patents, except as hereinafter pointed out. The general arrangement of the machine is as usual, with the sewing shaft 18 located behind and above the point of operation of the stitch-forming devices and substantially parallel to the line of the seam formed thereby.

The work is fed in the illustrated machine, as in the machine of Patents Nos. 1,824,063 and 2,271,611, by the movement of the work support 20 and presser foot while clamping the work. As best shown in Fig. 6, the presser foot 14 is secured to the forward end of a substantially horizontal presser foot lever 20 pivotally mounted at 22 on the feed carriage to which is also secured the cooperating work support.

The mechanism for imparting a feeding movement to the work support and presser foot while clamping the work is the same as in the machine of Patent No. 2,271,611 and includes a cam 24 on the main sewing shaft 18, a cam lever 26, a link 28 connecting the cam lever with the central joint of a pair of toggle links 30 and 32. The toggle link 30 is pivotally mounted on a yoke 34 and the other link 32 is connected to a rearwardly extending arm on a feed carriage 36 having a lug for the pivotal mounting 22 for the presser foot lever 20. The particular construction of the present feed carriage differs slightly from that of Patent No. 2,271,611 in that the present carriage is formed as a single integral piece whereas the carriage of the said patent is formed in two parts clamped together on an inclined pivot shaft corresponding to the shaft 38. The pivot shaft 38 is rotatably supported in bearings in the machine frame and is held from lengthwise movement by clamp collars 40 on the shaft.

As has been stated, an important feature of the invention relates to an arrangement of the work support and presser foot acting as a unit 50 to exert a continued rearward pull at right angles to the line of feed on the outsole of a shoe adjacent the point of sewing operations. In the embodiment of this feature, the work support 12, which is of U-shape, is clamped to parallel portions of the feed carriage 36 and has a table portion formed along its work-engaging surface with a raised portion 42 at the extreme left end of the work engaging surface, as shown in Fig. 3, for causing the pressure exerted on the work to be centralized at a mid-point such as 44 (Figs. 4 and 5) on the portion 42 as the work is clamped by the presser foot, the work-engaging surfaces of the work support and presser foot being elsewhere inclined away from each other in a direction opposite to that of work feed. While the work engaging surfaces of both work support and presser foot may be inclined for this purpose, the present machine is illustrated as having the work engaging surface of the work support only inclined. Inclining the work-engaging surfaces of the work support and presser foot away from each other in a direction opposite to that of work feed provides a means for enabling the pressure on the work to be centralized at the mid point 44. During successive feeding movements

of the work support, the movements imparted to the work, unless otherwise prevented, are substantially the same as the movements of the midpoint 44, this being the center of greatest work clamping pressure.

Referring to Figs. 4 and 5, the pressure-centralizing portion 42 is indicated by a somewhat D-shaped outline and is located on the work support at the seam side of the needle and awl paths so that in feeding the work it moves from the full-line position to the dot-dash line position always further away from a point 45 formed by the intersection of a line 46 passing through the center of the pivotal mounting shaft 38 at right angles to the line of feed indicated at 48, the line of feed passing through the needle and awl paths. The needle and awl paths are coincident in the illustrated machine at the location of the awl 4. The awl 4 is located at the trailing side of the intersection 45, or at the left as viewed from the front of the machine, the pressure-centralizing point 44 on the work support being located still further to the left of the awl away from the intersection 45. As a result of the swinging movement of the work support about the shaft 38, the pressure centralizing point 44 moves appreciably out of the line of feed along an arcuate path 50 and rearwardly by a distance 52 in feeding the work. Since the work is clamped by the work support and presser foot during feeding movement, a rearward pull is exerted on the work itself. Back-feeding movement of the work support and presser foot occurs when the clamping pressure of the foot is released from the work so that during back-feeding movement the pressure-centralizing portion 42 of the work support moves from the dot-dash position to the full-line position and with a forward thrust against the shoe being sewn through the distance 52. In the full-line position of the pressure-centralizing portion 42, the work is again clamped so that the rearward pull which is directed at right angles to the line of feed is continued from one sewing cycle to another, the awl being projected into and holding the work during each back-feeding movement.

The rearward pull of the work support and presser foot on the work has further desirable results due to the inclination of the pivotal mounting shaft 38 for the feed carriage, as indicated in Fig. 6. In sewing about the shank of a Goodyear welt shoe 54, shown in Fig. 7, and about the entire marginal portion of other types of shoes, a front surface 56 of the work support disposed at an angle to the work-supporting and pressure-centralizing surfaces serves as a gage against the outer last-supported surface of the shoe upper indicated at 58. In a Goodyear welt shoe, the shoe is presented by the operator in the position shown with the upper against the gage surface 56 and with the projecting margin of welt 60 on the work-supporting surface. The angle of the pivotal mounting shaft 38 is such that the forward thrust movement of the work support during back feed of the work support causes the gage surface 56 and the work-supporting surface of the table portion on the work support to be urged with equal pressures against both the upper and welt within the crease of the shoe while the clamping pressure of the presser foot is released. The inclination of the shaft 38 for this purpose is selected at an angle which will cause a line 62 bisecting the angle between the work gage and supporting surfaces on the table portion of the work support to intersect the

axis of the shaft 38 at right angles, the forward thrust of the work support when so arranged being exerted along this line.

In order to enable the operator to hold the work against the back gage with little or no muscular effort, according to present day practices, a shoe is presented to the machine with the edges of the welt and outsole substantially out of parallel to the line of feed 48. During feeding movements of a shoe so presented to the present machine, there is a tendency to choke or retard the feeding movement of the shoe whenever a back gage for guiding the rearward edges of the work is employed. With the present construction and mode of operation, the rearward pull exerted by the work support and presser foot on the work enables the operator to present the work with the sole edge more nearly parallel to the line of feed than possible heretofore, and at the same time, to hold the work against the back gage without substantial muscular effort.

As a means for accentuating the effects of rearward pull on the work, the feeding and back-feeding movements are so proportioned that the time of feed is relatively long, as compared with the time of back feed. When the machine is operating at high speeds, the inertia of a shoe is easily overcome during the relatively slow feeding movement and after the clamping pressure on the work is released, the relatively quick back-feeding movement enables a new clamping grip to be obtained on the work before any substantial forward movement of the work is possible.

Any link mechanism is subject to wear and 35 looseness in its pivotal connections after long continued use and to offset the effects of wear and lost motion in the work-feeding mechanism of the present machine, the rearwardly extending arm of the feed carriage 36 is acted upon by a 40 plunger 64 slidable in a passage in the machine frame and backed by a compression spring 66. The spring 66 is retained in the passage of the frame by a cap screw 68. By reason of the relatively long feeding movement imparted to the 45 feed carriage by the feeding mechanism, it is possible for a light spring acting on the plunger 64 to take up all of the backlash in the feeding mechanisms even when the machine is operating at high speeds.

50 The back gage is similar to that of the machine disclosed in Patent No. 2,271,611 and is located with the trailing end of its work-engaging edge, or of that portion of the edge from which the work recedes, in close proximity to the portion 55 42 of the work support which acts to concentrate the pressure on the work, as indicated in Fig. 3. With the end of the back gage so located, the operator is enabled to guide the work more effectively and to change its position easily while presenting the work to the machine.

To prevent the outer lower corner of the welt from becoming wedged or cut between the work support and the back gage as the work is compressed by the presser foot, the present back gage is provided with a lip 70 having a horizontal work-engaging surface substantially parallel to the work engaging surface of the work support in front of the vertical work-engaging portion of the back gage, as shown in Figs. 2 and 3. The 65 angularly disposed surfaces formed by the lip 70 and the vertical edge-engaging surface of the back gage provide a trough through which the outer lower corner surfaces of the welt travel. To enable the lip to approach as close as possible 70 to the work-engaging surface of the work sup-

port, the work support is cut away at 72 to form a shoulder 74. During back-feed movement of the work support, the shoulder 74 moves toward the lip on the back gage and raises the edge of the welt onto the surface of the work support.

The nature and scope of the invention having been indicated and a particular embodiment of the invention having been described, what is claimed is:

1. An outsole shoe-sewing machine having, in combination, stitch-forming devices, a work support and a presser foot for clamping and feeding the work, and means for actuating the work support and presser foot to cause them to exert a continued pull on the work directed rearwardly of the line of the seam during successive work feeding movements.

2. An outsole shoe-sewing machine having, in combination, stitch-forming devices, a work support and a presser foot for clamping and feeding the work, a carriage on which the work support and presser foot are mounted to move as a unit during work feed, and means for imparting a rearward movement to the carriage during feed and a forward movement during back feed of the work support and presser foot to cause a continued rearward pull to be exerted on the work at right angles to the line of the seam throughout successive work-feeding movements.

3. An outsole shoe-sewing machine having, in combination, stitch-forming devices including a needle, a work support and a presser foot shaped to exert a centralized clamping pressure on the work, a carriage on which the work support and presser foot are mounted to move as a unit, a shaft about which the carriage oscillates through a curved path during work feed, and mechanisms for actuating the presser foot and carriage in timed relation to cause the work to be clamped while those parts which centralize the clamping pressure move rearwardly of a line extending in the direction of feed and to release the work from the grip of the presser foot during the return movements.

4. An outsole shoe-sewing machine having, in combination, stitch-forming devices, a carriage, a shaft about which the carriage is mounted for oscillation, and a work-feeding support and a work-clamping presser foot on the carriage having work-engaging surfaces shaped to centralize the clamping pressure at a position with respect to the carriage shaft in which a rearward pull will be exerted on the work throughout each feeding movement.

5. An outsole shoe-sewing machine having, in combination, stitch-forming devices including a needle, a carriage, a shaft about which the carriage is mounted for oscillation, and a work-feeding support and a work-clamping presser foot on the carriage having work-engaging surfaces inclined one toward the other in the direction of work feed to cause the greatest clamping pressure to be exerted at a position on the seam side of the needle.

6. An outsole shoe-sewing machine having, in combination, stitch-forming devices, a work-feeding support, a work-clamping presser foot, and mechanisms for actuating the work support and presser foot at right angles to the line of feed to cause them to exert a relatively slow rearward pull on the work during feeding movements and a relatively quick forward thrust against the work during back-feeding movements.

7. An outsole shoe-sewing machine having, in combination, stitch-forming devices, a work-

feeding support having a table portion formed with work-engaging surfaces disposed at an acute angle to enter the crease between the welt and upper of a shoe, a work-clamping presser foot, a carriage on which the work support and presser foot are mounted to move as a unit, a shaft forming an axis about which the work support oscillates during work feed, the work-supporting surface of the work support and the work-clamping

10 surface of the presser foot being shaped to centralize the clamping pressure at one side of a line perpendicular to both said axis and the line of the seam throughout the feeding movements of the work support and presser foot, and a mechanism for actuating the carriage at right angles to the line of feed to cause the work support to be thrust along that part adjacent the center of clamping pressure into the crease between the welt and upper, the axis of the work support being disposed to cause the thrust to be exerted in the direction of a line approximately bisecting the angle of the work-engaging surface of the work support.

15 8. An outsole shoe-sewing machine having, in combination, stitch-forming devices, a work support and a presser foot for clamping and feeding the work, a carriage on which the work support and presser foot are mounted to move as a unit during work feed, mechanism including a train of 20 connections for actuating the carriage first with a relatively slow feeding movement and then with a relatively quick back-feeding movement, and yielding means acting on the carriage in the direction of the feeding movement to take up lost motion in the connections.

25 9. An outsole shoe-sewing machine having, in combination, stitch-forming devices, a work support and a presser foot for clamping and feeding the work, a back gage having a work-engaging 30 edge with its trailing end extending past the point of operation of the stitch-forming devices, and means on the work support and presser foot for concentrating the pressure on the work along the work-engaging surfaces of the work support and 35 presser foot in close proximity to the trailing end on the work-engaging edge of the back gage.

40 10. An outsole shoe-sewing machine having, in combination, stitch-forming devices, a work support and a presser foot for clamping and feeding the work, a back gage projecting above the work supporting surface of the work support for guiding the edge of the work on the work support and 45 having a work-engaging edge with its trailing end extending past the point of operation of the stitch-forming devices, means on the work support and presser foot for concentrating the pressure on the work along the work-engaging surfaces of the work support and presser foot in close proximity to the trailing end on the work-engaging edge of the back gage, and means for actuating the work support and presser foot to cause them to exert a continued rearward pull on the work against the back gage.

50 11. An outsole shoe-sewing machine having, in combination, stitch-forming devices, a work support and a presser foot for clamping and feeding the work, a stationary gage having angularly disposed surfaces one of which projects above the work supporting surface of the work support for 55 guiding the edge and support-engaging surfaces, respectively, of the work on the work support past the point of operation of the stitch-forming devices to prevent the work from becoming wedged between the work support and gage during feed- 60 ing movements of the support.

12. An outsole shoe-sewing machine having, in combination, stitch-forming devices, a work support and a presser foot for clamping and feeding the work, a stationary gage projecting above the work supporting surface of the work support for guiding the edge of the work past the point of operation of the stitch-forming devices, and a lip on the gage acting in advance of the work engaging surface of the work support to guide the support-engaging surface of the work to prevent the work from becoming wedged between the work support and gage during feeding movements of the support.

13. An outsole shoe-sewing machine having, in combination, stitch-forming devices, a work support and a presser foot for clamping and feeding the work, a stationary gage for guiding the edge of the work past the point of operation of the stitch-forming devices, a lip on the gage for guiding the support-engaging surface of the work to prevent the work from becoming wedged between the work support and gage during feeding movements of the support, and a shoulder formed on the work support at the side of the point of op-

eration of the stitch-forming devices first engaged by the work during back feed of the work support to permit the work-engaging surface of the lip to be located close to the work-supporting surface of the work support substantially in the same plane with the work-supporting surface.

14. An outsole shoe-sewing machine having, in combination, stitch-forming devices, a work support and a presser foot for clamping and feeding the work, means for actuating the work support and presser foot to cause them to exert a continuous rearward pull on the work, an edge gage having angularly disposed surfaces one of which projects above the work supporting surface of the work support to guide the edge and another of which is substantially parallel to the work engaging surface of the work support to guide the support-engaging surface of the work past the stitch-forming devices and to prevent the work from becoming wedged by the rearward pressure between the support and gage during feed.
